UNITED STATES PATENT OFFICE.

JOSEPH WOLFF, OF BROOKLYN, NEW YORK, ASSIGNOR TO SONORA PHONOGRAPH COMPANY, INC., A CORPORATION OF NEW YORK.

DESIGN FOR A RADIOCABINET.

Application filed October 27, 1926. Serial No. 19,492. Term of patent 7 years.

To all whom it may concern:

Be it known that I, JOSEPH WOLFF, a citizen of the United States of America, residing in the borough of Brooklyn, county of Kings, city and State of New York, have invented a new, original, and ornamental Design for Radiocabinets, of which the following is a specification, reference being had to the accompanying drawing, forming a part thereof.

The figure is a perspective view of a radiocabinet illustrating my new design.

I claim:

The ornamental design for a radiocabinet, substantially as shown.

This specification signed and witnessed this 13th day of October, 1926.

JOSEPH WOLFF.
